Robert D. Pearson
ATTORNEY.

UNITED STATES PATENT OFFICE.

ROBERT R. SMITH, OF LOS ANGELES, CALIFORNIA, ASSIGNOR TO LOS ANGELES RAILWAY CORPORATION, OF LOS ANGELES, CALIFORNIA.

COUPON TRANSFER.

Application filed November 21, 1922. Serial No. 602,395.

To all whom it may concern:

Be it known that I, ROBERT R. SMITH, a citizen of the United States, residing at Los Angeles, in the county of Los Angeles and 5 State of California, have invented certain new and useful Improvements in Coupon Transfers, of which the following is a specification.

This invention relates to coupon transfers 10 and the objects are first to provide a transfer bearing coupon which may be detached by the conductor of the second car on which the passenger rides; second, to provide a body of the transfer to be surrendered to 15 the conductor of a third car to limit the rides of a passenger; third to provide a transfer printed on a different color paper for the "in" and "out" trips, thereby permitting the printing on the reverse of the 20 transfer of all rules or restrictions applying to the use of the said transfer; fourth, to combine the use of an afternoon coupon, to indicate whether the transfer was issued before or after 12 o'clock noon; fifth, to 25 use a colored line letter superimposed on the face of the transfer to make it easy for receiving conductors to distinguish from what line the transfer is issued; and sixth, the use of various colored symbols also 30 superimposed on the face of the said transfer, to represent certain dates to eliminate the use of punching or printing the said dates thereon.

In the drawing Figure 1 represents the 35 front face of the coupon transfer, and Figure 2 represents the back face of the same coupon transfer.

Referring to the drawing in which like numerals of reference designate similar 40 parts, 14 represents the leaf which is divided into a transfer 1, a coupon 2 and a stub 3, which are joined together on the lines 12 and 11 respectively, and the line 13 in turn joins the stub 3 to the binder 10 which is 45 bound into a pad containing a predetermined number of leaves 14.

The front face of the said transfer 1 and coupon 2 are printed with letters 6 to represent the car line for which the said 50 transfer is issued, and the symbol 5 is in turn printed under the said letters 6 to represent the dates or months of the year for which the same transfer 1 and coupon 2 are valid, thus the car line and date for

which the transfer 1 and coupon 2 were 55 intended are legible to the car line issuing and receiving the same.

The designation portion 16 of the transfer 1 is legibly printed to name the in-trip or out-trip, to or from a certain terminal point 60 respectively, the emergency portion 17 of the transfer 1 is printed with a customary word, or phrase, to validate the transfer 1 on parallel lines in case of a blockade, or to return in the opposite direction in the same 65 line, and the extension portion 18 is in turn printed with significant words or phrases to validate the transfer 1 for use at transfer points reached after the car has been diverted from its own line, or to validate the 70 same to a continuous passage beyond the turn-back point.

The numbers 15 indicate the time of the 75 day or night for which the transfer 1 is valid when punched accordingly, and the punch mark 4 indicates that the transfer 1 is valid the morning following the time for which the same was punched.

The numbers 7 are printed consecutively 80 on the leaves 14 throughout the pad, and the same numbers 7 appear on the respective transfer 1 and coupon 2.

The stub 3 is printed to designate that the transfer 1, and coupon 2 are valid at a certain time of the day, by printing the 85 rules 22 thereon.

The identification 19 is printed on the transfer 1 to designate the car line issuing the same and the route over which the same is valid. 90

The rules 20, 21 and 22 are printed on the front face of the transfer 1, coupon 2 and stub 3, respectively, and define the time limits for the validity of the said transfer 1, coupon 2 and stub 3, and conditions of presentation. The rules 8 and 9 are printed on the back face of the transfer 1 and coupon 2 respectively, and confines the use thereof to certain transfer points. 95

When selecting a transfer stub 10 for a 100 certain car line, with its stub 3, transfer 1 and coupon 2 connected thereto as hereinbefore described, the letter 6 in the phantom or colors will facilitate the recognition thereof in connection with the identification 19, and the symbol 5 in turn gives the date thereof with the said letter 6 and identification 19, and the combined symbol 105

5 and letter 6 in turn indicate the service line on which the transfer is to take place, and the date thereof.

When a transfer is issued for use from one car to another in the morning the same is removed from the binder 10 and the stub 3 by tearing on the line 11 and the transfer 1 and coupon 2 are then presented to the passenger by being joined together on the line 12, and when a transfer is issued for use from one car to another in the afternoon the same is removed from the binder 10 by tearing on the line 13, the same transfer 1 and coupon 2 are presented with the stub 3 joined thereto on the line 11.

The time of the day when the transfer was issued is indicated by punching holes through the correct combination of numerals 15, the punch mark 4 is punched with a hole through the transfer 1 if the same is valid for the following morning after the date thereof, the designation portion 16 of the transfer 1 is punched with a hole therethrough when the same is for an out-trip 25 or in-trip and states the designation thereof, the emergency portion 17 of the transfer 1 is punched with a hole therethrough when the said transfer 1 is to be used on a parallel line, and the extension portion 18 is punched 30 with a hole therethrough when the same transfer is to be used when the car is being diverted, or turned back, from the designated line and the passenger is to receive a transfer on another car, or car line.

35 The rules 8, 9, 20 and 21 are intended to be read by the passenger receiving the transfer 1 and coupon 2, to legalize the possession and use thereof.

Having thus described my invention 40 what I claim is:

1. A coupon-transfer book of the class described, the combination of a stub-transfer connected to the said book, adapted to indicate an afternoon transfer; a coupon, adapted to be connected to the said stub-transfer; a letter-symbol means, adapted 45 to indicate the service line and date of the said stub-transfer and coupon, as set forth.

2. A coupon-transfer of the class describ-

ed, adapted to be bound into a book, in combination with a stub connected to the binder portion of the said book; a transfer, adapted to be connected to the said stub; a coupon, adapted to be connected to the said transfer; a service line letter on the said transfer and coupon, adapted to distinguish the issuing car line; an identification means integral with the said stub, adapted to indicate an afternoon transfer, as set forth. 50

3. A coupon-transfer of the class described, the combination of a stub portion integral with the said coupon-transfer; a transfer portion positioned adjacent to the said stub portion, a coupon portion positioned adjacent to the said transfer portion; a letter-symbol means superimposed on the said transfer portion and coupon portion, adapted to indicate the service line and date of the transfer; an identification portion of the said transfer, adapted to designate the time, place and direction thereof, 55 as set forth.

4. A coupon-transfer book of the class described, the combination of an afternoon-transfer portion, adapted to be removed from the coupon-transfer; a transfer-body portion integral with a coupon-transfer; a coupon-transfer portion, adapted to be removed from the said transfer-body portion; a code means superimposed on the said transfer-body portion and the coupon-transfer portion, adapted to indicate the service line and date of the said transfer; a morning transfer portion integral with the said transfer-body portion, adapted to indicate a transfer the morning following the date of issue; an emergency portion integral with the said transfer-body portion, adapted to indicate a transfer to a parallel line; an extension portion integral 60 with the said transfer-body portion, adapted to indicate a transfer to a diverted car line; a designation portion, adapted to indicate the direction of the transfer, as set forth. 65

In testimony whereof I affix my signature. 70

ROBERT R. SMITH.
